HAT FASTENING DEVICE

Otto E. Seiffert, Union, N. J., assignor to Samuel Getmansky, New York, N. Y.

Application May 7, 1936, Serial No. 78,373

9 Claims. (Cl. 132—58)

This invention relates to new and useful improvements in a hat fastening device and process for manufacturing the same.

The invention has for an object the construction of a hat fastening device which is characterized by an end element in the form of a body having an element for engaging a needle by which it may be drawn through cloth or similar material, and a member portion on the body for 10 clamping or holding the end of a cord.

A further object of the invention is to arrange the cord so that it extends towards the element on the body. When thus constructed it is possible to manufacture two of the bodies initially 15 integral with each other so as to be engageable upon a cord and subsequently to be cut apart. This process materially reduces the cost of manufacture of the hat fastening device.

A further object of this invention is to make 20 it possible to adapt the process to other types of body members (not necessarily having elements for engagement by a needle) to also reduce the cost of manufacture of such devices.

Still further the invention proposes constructing the element which is adapted to engage a 25 needle in the form of a hook loosely engageable into the eye of the needle. It is then contemplated to magnetize the needle so that the body will be held with sufficient firmness to the needle 30 to permit the needle and body to be readily drawn through cloth material or other similar material.

A further object of the invention is to teach 35 the construction of a modified form in which magnetization of the needle is not necessary. In this form it is proposed that complementary 40 bayonet elements be formed upon the fastening device and the needle by which these parts may be temporarily connected with sufficient rigidity so that they may be threaded through cloth or 45 similar material.

In another form of the invention it is proposed 50 to utilize the resiliency of the hook element of the body to engage a transverse holding slot on the needle for connecting the needle and body 55 together during the engagement of these parts through cloth or similar material.

A still further modified form of the invention 55 contemplates the use of an arcuate body formed with a piercing point at one end by which it may be engaged into and substantially screwed through cloth or similar material, and providing a projecting body with a member on the center thereof for clamping and holding the end of a 60 cord.

Another object of the invention is the construction of a device as described which is simple and durable and which may be manufactured and sold at a reasonable cost.

For further comprehension of the invention, and of the objects and advantages thereof, reference will be had to the following description and accompanying drawing and to the appended claims in which the various novel features are more particularly set forth.

In the accompanying drawing forming a material part of this disclosure:—

Fig. 1 is an elevational view of a hat fastening device constructed according to this invention.

Fig. 2 is an enlarged view of one end of the hat fastening device shown in Fig. 1, and a needle with which it may be drawn through cloth or similar material adjacent thereto.

Fig. 3 is an edge elevational view of Fig. 2.

Fig. 4 is an elevational view of a pair of end 20 elements of adjacent hat fastening devices before they are cut apart, appearing during the process of manufacture.

Fig. 5 is a view similar to Fig. 4 but showing 25 the same process applied to a different type of end element.

Fig. 6 is an edge elevational view of the end 30 element of a hat fastening device and a needle associated therewith, and these parts being provided with a novel arrangement for holding them temporarily firmly connected.

Fig. 6a is an enlarged detailed view of the holding 35 end portion of the needle shown in Fig. 6.

Fig. 7 is a plan view of Fig. 6.

Fig. 8 is an elevational view of the end element 35 of a hat fastening device constructed according to another embodiment of this invention.

Fig. 9 is a combined view of the edge of the end element shown in Fig. 8 and a needle adapted 40 to be associated therewith.

Fig. 10 is an elevational view of an end element 45 of a hat fastening device constructed according to another modification of the invention.

Fig. 11 is an edge elevational view of Fig. 10 looking in the direction of the line 11—11 thereof.

In Fig. 1 a hat fastening device is shown which 50 comprises a cord 10, preferably elastic, upon the ends of which there are end elements 11. Each of these end elements comprises a longitudinal body 11a formed with an element 11b on one end thereof for engaging a needle 12 by which the end element may be drawn through cloth or similar material. A member 11c is arranged on the other end of the body 11a for clamping or holding the 55 end of the cord 10. The cord 10 extends towards

the element 11b so that when it is engaged through cloth material or the like the end element will be transversely upon the rear of the cloth material and act as an anchor.

- 5 A feature of the construction of the end element 11 is that it has no sharp points. The element 11b is in the form of a hook which is not sharp. Heretofore, hat fastening devices have been manufactured which included piercing points. 10 As such hat fastening devices are mounted into sweat bands and linings of ladies' hats they are exposed, and quite often during the handling of the hat one is apt to have a finger pricked. The needle 12 is merely formed with an eye 12a at one 15 end adapted to engage the hook 11b. The other extremity of the needle is formed with a sharp point 12b. The needle is merely used for pulling the end element through cloth or similar material and then is disengaged from the end element. 20 In order that the parts be connected with sufficient rigidity during the time they are drawn through the cloth material it is advisable that some holding arrangement for these parts be provided. A preferred form would be to magnetize 25 the needle 12 and to have the end elements of steel or similar material which is attracted by magnetism. The parts will then be held together as required.

The invention also proposes a process by which 30 the hat fastening devices may be manufactured at an exceptionally low cost. Heretofore it was common to manufacture similar hat fastening devices by a process which consisted essentially in cutting elastic cords to desired lengths and attaching end elements singly upon the ends thereof. According to this new process it is proposed to construct the end elements in connected adjacent pairs, as shown in Fig. 4. The integral pair of end elements are stamped from sheet material so as to have a body portion 11aa, elements 40 11bb on the ends thereof for engaging a needle by which the hat fastening device may be drawn through cloth or similar material, and a member 11cc at the center for being clamped on and holding 45 a cord 10'. These double end elements are attached along the length of the cord at predetermined spaced positions, depending upon the length to which it is desired to have the cord of the hat fastening device.

50 Another step of the process consists in shearing, cutting or breaking the body 11aa upon the line XX. This line passes through the center of the member 11cc. Thus the two end elements are severed from each other.

55 In Fig. 5 a different type of hat fastening device is shown to which the same process is applied. In this form many of the parts may be identical and may be recognized by the same reference numerals, but which distinguishes from the prior 60 form merely in the elements 21bb. These elements are pointed and constitute piercing elements so that the hat fastening device may be drawn through cloth or similar material without the necessity of a needle.

65 In Figs. 6, 6a, and 7 another modification of the invention has been disclosed. According to this form there is a needle 12' which has a piercing end 12b and an eye opening 12a. Immediately adjacent the outer end of the eye opening 12a 70 there is a V-shaped groove 12c. The adjacent end of the eye opening 12a is formed with a wedge shaped slope 12d. The hook 11bb has its extremity bent inwards as clearly shown in Fig. 6. When the hook 11bb is engaged through the eye 12a of 75 the needle and the end element and the needle

drawn apart, the end of the hook will be camed open by the wedge shape 12d, and then engage into the groove 12c. It is shown in this position in Figs. 6 and 7. This connection is sufficient to firmly hold the parts during the period they are passed through cloth or similar material.

In Figs. 8 and 9 a still further modified form of the invention is disclosed in which the end element comprises a body 31a having a round inert end 31b. This body is also provided with a member 31c at its other end which clamps upon and holds the cord 10. This member 31c is formed with a bayonet slot 32, clearly shown in Figs. 8 and 9. This bayonet slot is adapted to be engaged by the complementary bayonet element 12aa of a needle 12''. The bayonet element 12aa is adapted to be forced into the base or inner end of the bayonet slot 32 and this connection will be sufficient to hold the parts while they are being threaded through cloth material or the like. The advantage of this arrangement resides in the fact that the body 31a does not need an independent element by which the needle may be connected. In Figs. 10 and 11 a further modification of the invention is disclosed in which the end element of a hat fastening device is shown and comprises an arcuate body 41a formed with a piercing point 41b at one end thereof and adapted to be screwed through cloth or similar material. A member 41c is formed intermediate of the ends of the body 41a and clamps and holds the end of the cord 10. This member 41c comprises merely a loop stamped from the material of the body 41a. After this end element has been screwed through cloth material it acts as a button upon the end of the cord 11 and so maintains its position.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new and desire to secure by United States Letters Patent, is:—

1. In a hat fastening device, a blunt elongated body formed at one end with an element for engaging a needle by which the body may be drawn through cloth or similar material, a cord, and a member on the body for clamping and holding the end of said cord so that the cord extends outwards from a point intermediate of the ends of said body.

2. In a hat fastening device, a blunt elongated body formed at one end with an element for engaging a needle by which the body may be drawn through cloth or similar material, a cord, and a member on the body for clamping and holding the end of said cord so that the cord extends outwards from a point intermediate of the ends of said body, said element comprising a hook adapted to engage a point of said needle.

3. In a hat fastening device, a blunt elongated body formed at one end with an element for engaging a needle by which the body may be drawn through cloth or similar material, a cord, and a member on the body for clamping and holding the end of said cord so that the cord extends outwards from a point intermediate of the ends of said body, said member comprising body

portions integral with the side of the body and clamped over the ends of the cloth.

4. In a hat fastening device, a blunt elongated body formed at one end with an element for engaging a needle by which the body may be drawn through cloth or similar material, a cord, and a member on the body for clamping and holding the end of said cord so that the cord extends outwards from a point intermediate of the ends of said body, said element comprising a bayonet element adapted to engage a complementary bayonet element on the needle.

5

5 5. In a hat fastening device, a blunt elongated body formed at one end with an element for engaging a needle by which the body may be drawn through cloth or similar material, a cord, and a member on the body for clamping and holding the end of said cord so that the cord extends outwards from a point intermediate of the ends of said body, said body being made of material attracted by magnetism, and a magnetized needle for the purpose mentioned above.

10

6. In a device of the class described, a body formed with an element for engaging a needle by which the body may be drawn through cloth or similar material, a member on the body for clamping and holding the end of a cord so that the cord extends towards said element, a needle with an eye and having a transverse slot adjacent the outer end of said eye, the outer end of said eye being formed with a wedge slope, and said element on the body being in the form of a hook

having an inturned end adapted to be forced up through the wedge slope and into the transverse slot when the hook is engaged in to the eye of the needle and the needle and body are drawn apart.

15

7. A process for manufacturing a hat fastening device consisting of securing a cord to the central portion of a member having elements at its ends which are adapted to be inserted through cloth or similar material, and then cutting the member and cord through said central portion to form two independent hat fastening device end elements upon the ends of said cords.

10

8. A process for manufacturing a hat fastening device consisting in securing a plurality of members having elements at their ends which are adapted to be inserted through cloth or similar material at their centers at spaced distances upon a cord, and then cutting the members and cord through said centers to form independent hat fastening device end elements upon the ends of the cords.

15

9. A process for manufacturing hat fastening devices, consisting of attaching on a cord in properly spaced positions at their central portions a plurality of members which are adapted to be inserted through cloth to act as a fastening device, and then cutting the connected cord and members apart at the centers of said members to form separate hat fastening devices.
